APPARATUS FOR WASHING CLOTHES

Jabez C. Nelson, Syracuse, N. Y., assignor to Easy
Washing Machine Corporation, Syracuse, N. Y.,
a corporation of Delaware

Application August 21, 1933, Serial No. 686,170

12 Claims. (Cl. 259—101)

This invention relates to new and useful improvements in apparatus for washing clothes, and constitutes a continuation in part, of my copending application, Serial No. 666,338, filed April 5 15th, 1933.

In the above-mentioned copending application, I have described a novel method of and apparatus for washing clothes in which a dolly or agitator having a plurality of blades is mounted in a 10 vat, the blades and central portion of the dolly being so arranged that when the dolly is oscillated, the contents of the vat are circulated in one general direction around the vat. As the clothes circulate around the outer circumference 15 of the vat, they rise upwardly toward the surface in a somewhat spiral curve and then are drawn inwardly toward the center where the clothes are subjected to an action which I have characterized as an individual action on the clothes as distinguished from a collective action.

An object of my present invention is to provide an agitator of the general above-described type in which a plurality of curved and inclined blades are mounted on a downwardly and outwardly extending surface, such as that presented by a cone, and at the base of the cone, there is provided a dilated or sharply defined outwardly extending surface forming a corniculum which serves to direct the clothes, as they are thrown downwardly and outwardly by the blades and cone-shaped surface, more sharply toward the sides of the vat.

Another object of my invention is the provision of a guard at the bottom of the agitator located 35 in the central bore thereof to prevent clothes from accidentally getting inside of the agitator.

A further object of my invention is to provide, in connection with an agitator of the general above-described type, a hat-shaped member or 40 cap adapted to be supported on the top of the agitator at the normal surface level of cleansing fluid to mark the desired level thereof.

Still another object of my invention is to provide a cap mounted on a cone-shaped dolly having 45 curved and inclined blades extending from the surface thereof, the cap having a surface meeting the upper edges of the blades and extending outwardly parallel to the surface level of cleansing fluid whereby, when the dolly is oscillated, splashing of cleansing fluid is minimized.

Other objects and advantages will be more apparent from the following description, taken in connection with the accompanying drawing, in 50 which:—

Figure 1 is a perspective vertical view showing my novel agitator.

Figure 2 is a vertical cross sectional view showing my novel agitator mounted on a washing vat.

Figure 3 is a view taken on line 3—3 of Figure 2.

The agitator of my invention may be mounted in any suitable vat or tub having side walls 11 and a bottom 12. The bottom of the vat at substantially its central portion is provided with an opening for the reception of one end of an upstanding sleeve 13 secured to the bottom 12 of the vat in any suitable water-tight manner. The sleeve 13 at its upper end, is provided with a bushing 14 which is supported internally of the sleeve by a 10 flange 16 mounted internally of the sleeve. The bushing 14 constitutes an upper bearing for an oscillatable dolly shaft 17 which extends upwardly from a point without the vat to a point 15 above the bushing 14.

Any usual and well-known means may be provided for oscillating the dolly shaft through a desirable arc as, for instance, 200 degrees more or less, and there is here shown a gear 19 mounted on the shaft for rotation therewith and adapted 25 to be driven in reverse directions by a segmental gear or rack 21 reciprocated by any suitable mechanism well-known in the art to which this invention applies.

The dolly shaft 17 projects above the bushing 30 14 and is formed at its upper end with lengthwise splines or grooves 22 for inter-engagement with corresponding splines or grooves on a bearing member 23 permanently secured within the upper closed end 24 of the agitator, generally indicated 35 by the numeral 26. As shown in the drawing, the agitator has a central hollow bore concentric with the shaft 17 and the sleeve 13. Internally of the agitator near the bottom thereof, there is provided a plurality of, here shown as six, internally extending fins or projections 27 which are notched at 28 for the reception of a cup-shaped bearing member 29 which is affixed to the projections 27 and extends downwardly and inwardly to form a portion 31 which extends along 40 the sleeve 13 and rotates with respect thereto. In this manner, a driving connection and support for the agitator is provided by means of the dolly shaft itself and the agitator is guided by the bushing 14 and the guide bearing 29.

At the bottom of the agitator, mounted internally thereof, there is provided a circular shield or guard 32 preferably of aluminum or other suitable material having a circular opening for receiving the sleeve 13. The guard 32 is confined 55

between a packing ring 33 and a flange 34 formed on the sleeve 13. The guard 32 has a plurality of apertures 35 to permit the escape of fluid and slopes upwardly and outwardly to a point 36 and then extends downwardly to form a portion 37 which is closely fitted to the internal circumference of the agitator. The guard permits free circulation of fluid and provides additional protection, preventing clothes, especially small articles, from working their way into the interior of the agitator should they accidentally become caught between the agitator and the bottom of the vat.

At the top of the agitator, I have provided a means of adjusting the position of the bottom of the agitator with respect to the bottom of the vat which comprises, as here shown, a threaded member 38 which extends through an aperture formed in the upper closed end 24 of the agitator and contacts with the upper extremity of the shaft 17. A lock nut 39 is provided for locking the threaded member in position after the desired adjustment has been made.

The outer surface of the agitator 26 is preferably cone-shaped in form, the angle of inclination of the cone surface to the bottom of the vat being any desired amount, but preferably approximately ten degrees. A plurality of blades 41 extend outwardly from the cone surface and curve downwardly and around said surface any desired amount, preferably approximately 180 degrees. In order to distinguish the surface of the blades designated, I have termed one surface indicated by the numeral 42 the leading surface and the other surface indicated by the numeral 43, the following surface.

At a point indicated by the numeral 44, the blades are substantially normal to the surface of the cone, but toward the bottom, the blades are inclined with a gradually increasing inclination so that the leading surface 42 lies at an acute angle and the following surface at an obtuse angle with reference to the cone surface. The edge of the leading blade surface 42 is preferably beaded, as indicated at 45 so that a smooth edge 45 is presented to the clothes and also to permit the use of a thinner blade which is found to be of advantage in producing a more efficient agitator. The blades 41 gradually increase in width toward the bottom of the vat and at the bottom of the agitator, merge into a dilated or sharply outwardly curved portion 46 forming with the cone, a corniculum, for a purpose hereinafter to be described. By the term "corniculum" as herein used, I mean a structure having an elongated 55 preferably cone-shaped surface terminating in a dilated portion and forming a structure which may be described as trumpet-shaped. Preferably the lower ends of the blades extend outwardly some distance beyond the periphery of the flange 60 46, as shown in the drawing, so that the blades constitute the margins of channels extending downwardly from substantially the normal surface of cleansing fluid and opening toward the bottom of the vat.

On the top of the agitator, I have provided a hat-shaped member or cap 47 which is adapted to fit snugly over the upper closed end 24 of the agitator, seat itself in a groove 58 formed therein and be held in position by a screw 48 threaded into the threaded member 38. The cap 47 may be of any desired shape, but preferably extends downwardly and outwardly to a point 49 from which the sides extend vertically downward to form a circular ring 51 at about the normal surface level 70 of cleansing fluid. A circular bead 52 is formed

around the ring 51 and indicates the level to which the washing vat should normally be filled with cleansing fluid and clothes in order to obtain the maximum efficiency in operation. At the bottom of the cap, a surface 53 is formed which contacts with the upper edge of the blades and is supported thereby.

As more fully described in my above-mentioned co-pending application, upon rotation of the agitator in a clockwise direction, the cleansing fluid and clothes are caught in the blades and are drawn downwardly and outwardly toward the bottom and sides of the vat and circulated in a clockwise direction around the vat. Upon reversal, because of the curvature and inclination 15 of the following surface 43, no substantial reversal of the contents of the vat occurs, the agitator, to a certain extent, merely sliding through the water and tending to throw the clothes outwardly toward the sides of the vat away from the 20 agitator. Upon again reversing, a new batch of clothes is caught in the blades and hurled downwardly and outwardly around the vat in a clockwise direction. As the clothes circulate around the vat, they gradually rise to the surface, the path of movement being somewhat 25 spiral in form, and upon reaching the surface, they are drawn inwardly toward the center of the vat to be subsequently caught by the blades and thrown downwardly and outwardly as above. 30 described.

As the clothes are drawn and circulated across the surface, the action more fully described in my copending application, which I have characterized as an individual action on the clothes, as 35 distinguished from a collective action, occurs. Each article of clothing is individually caught by the blades, unfurled and flexed backwardly and forwardly by the reversals of the agitator, it usually requiring several reversals before each 40 article is entirely, so to speak, swallowed by the blades and thrown downwardly and outwardly.

I have found that by utilizing a structure in the shape of a corniculum or a cone surface with a flange sharply outwardly extending, as described above and indicated by the numeral 46, 45 that the action of drawing the clothes downwardly from the surface and throwing them outwardly toward the sides of the vat, is aided, so that a much more efficient operation is secured. 50

While the water line of the vat has been indicated as slightly above the upper extremity of the blades, when the agitator is oscillating, it tends to throw the water and clothes outwardly towards the sides of the vat so that the water line 55 is depressed adjacent the agitator and lies at or slightly below the upper extremity of the blades. During operation, especially upon rotation of the agitator in a clockwise direction, there is a tendency to cause a slight splashing adjacent the 60 agitator, and by utilizing the cap which is closely confined over the upper extremities of the blades, the splashing is eliminated. The cap, in addition, tends to lend a more finished appearance to the agitator and serves as a convenient means 65 for marking the normal surface level of cleansing fluid.

Although I have shown and described a specific form and construction of apparatus as constituting an embodiment of the invention, I do 70 not wish to restrict myself to the details shown, as various changes and modifications may be readily made, without departing from the scope of my invention, as set forth in the appended claims.

I claim:

1. In a machine for washing clothes, a washing vat having a normal surface level of cleansing fluid, an oscillatable agitator mounted in said vat, said agitator comprising an upstanding central portion, a plurality of blades extending outwardly from said central portion, a cap mounted on the top of said agitator at substantially the normal surface level of cleansing fluid, said cap having a surface of substantial area extending outwardly parallel to and facing the surface of the cleansing fluid, and means for oscillating said agitator. 5
2. In a machine for washing clothes, a washing vat having a normal surface level of cleansing fluid, an oscillatable agitator mounted in said vat, said agitator comprising an upstanding central portion, a plurality of blades, extending outwardly from said central portion, a cap mounted 10 on the top of said agitator at substantially the normal surface level of cleansing fluid, said cap having a surface extending outwardly parallel to the surface of the cleansing fluid and meeting the upper edges of the blades, and means for oscillating said agitator. 15
3. In a machine for washing clothes, a washing vat having a normal surface level of cleansing fluid, an oscillatable agitator mounted in said vat, said agitator comprising an upstanding central portion, a plurality of blades extending outwardly and curved downwardly and around said central portion, a cap mounted on the top of said agitator at substantially the normal surface level of cleansing fluid and having 20 a surface of substantial area facing the top surface of the cleansing fluid, and means for oscillating said agitator. 25
4. In a machine for washing clothes, a washing vat having a normal surface level of cleansing fluid, an oscillatable agitator mounted in said vat, means for oscillating said agitator, said agitator comprising an upstanding central portion, a plurality of blades extending outwardly and curved downwardly and around said central portion, and a cap mounted on the top of said agitator at substantially the normal surface level of cleansing fluid, said cap having a surface extending outwardly parallel to the surface of the cleansing fluid and meeting the upper edges of the blades. 30
5. In a machine for washing clothes, a washing vat having a normal surface level of cleansing fluid, an oscillatable agitator mounted in said vat, means for oscillating said agitator, said agitator comprising an upstanding cone-shaped central portion, a plurality of blades curving downwardly and around said cone-shaped central portion and inclining with respect thereto, and a cap mounted on the top of said central portion at substantially 35 the normal surface level of the cleansing fluid, said cap having a surface exposed to the top surface of the cleansing fluid and adapted to prevent splashing of the fluid upwardly. 40
6. In a machine for washing clothes, a washing vat having a normal surface level of cleansing fluid, an oscillatable agitator mounted in said vat, means for oscillating said agitator, said agitator comprising an upstanding cone-shaped central portion and a plurality of blades curving downwardly and around said cone-shaped central portion and inclining with respect thereto, and a cap mounted on the top of said agitator at substantially 45 the normal surface level of cleansing fluid, said cap having a surface extending outwardly parallel to and facing the surface of the cleansing fluid and meeting the upper edges of the blades. 50
7. In a machine for washing clothes, a washing vat having a normal surface level of cleansing fluid, an oscillatable agitator mounted in said vat, 5 means for oscillating said agitator, said agitator comprising a cone-shaped central portion extending substantially from the normal surface level of cleansing fluid to the bottom of the vat and having at the bottom thereof, an outwardly 10 extending flange, and a plurality of blades extending outwardly and curving downwardly and around said cone-shaped surface and inclined with respect thereto, and a cap mounted on the top of said agitator at substantially the normal surface level of cleansing fluid, said cap having a surface extending outwardly parallel to the surface of the cleansing fluid and meeting the upper edges of the blades. 15
8. In a washing machine, a vat, an oscillatable agitator mounted in and extending substantially to the bottom of the vat and having a hollow bore, means for oscillating and supporting said agitator comprising a motor driven shaft, a perforated stationary shield mounted at the bottom 20 of the vat and substantially closing said hollow bore, said shield having a surface in running engagement with said agitator. 25
9. In a machine for washing clothes, a washing vat having a normal surface level of cleansing fluid, an oscillatable agitator mounted in such vat, means for oscillating said agitator, said agitator comprising an up-standing central portion and a plurality of blades extending substantially from the top of said central portion downwardly 30 and curving in the same direction around the surface of said central portion, means for preventing splashing of the washing fluid comprising a cap having a surface of substantial area facing the cleansing fluid and extending substantially parallel thereto, said cap being mounted on said agitator at substantially the normal surface of 35 cleansing fluid. 40
10. In a machine for washing clothes, a washing vat having a normal surface level of cleansing fluid, an oscillatable agitator mounted in said vat, means for oscillating said agitator, said agitator comprising an up-standing central portion and a plurality of blades extending substantially from the top of said central portion downwardly 45 and curving in the same direction around the surface of said central portion and said blades being inclined in the same direction with respect to the axis of said central portion, means for preventing splashing of the washing fluid comprising a cap having a surface of substantial area facing the cleansing fluid and extending substantially parallel thereto, said cap being mounted on said agitator at substantially the normal surface level of 50 cleansing fluid. 55
11. In a washing machine, a vat, an oscillatable agitator extending upwardly from substantially the bottom of the vat and having a hollow bore, means for oscillating and supporting said agitator comprising a motor driven shaft, a sleeve concentric with said shaft and extending upwardly to a point above the normal liquid level in the vat, a member in said hollow bore secured to said agitator and having a running fit with said sleeve, and a shield for preventing clothes from being 55 caught beneath the agitator, said shield being stationary with respect to the agitator and substantially closing the lower end of said hollow bore. 60
12. In a washing machine, a vat, an oscillatable agitator extending upwardly from substantially 65 the bottom of the vat and having a hollow bore, means for oscillating and supporting said agitator comprising a motor driven shaft, a sleeve concentric with said shaft and extending upwardly to a point above the normal liquid level in the vat, a member in said hollow bore secured to said agitator and having a running fit with said sleeve, and a shield for preventing clothes from being 70 caught beneath the agitator, said shield being stationary with respect to the agitator and substantially closing the lower end of said hollow bore. 75

the bottom of the vat and having a hollow bore, means for oscillating said agitator comprising a motor driven shaft, a sleeve extending upwardly through the bottom of the vat concentric with said shaft and internally of said hollow bore, a flange on said sleeve and a shield confined be-

tween said flange and the bottom of the vat, said shield being stationary with respect to the agitator, substantially closing the lower end of said hollow bore and forming a running fit with the agitator.

JABEZ C. NELSON.
